UNITED STATES PATENT OFFICE.

ARTHUR WHEATLEY, OF PHILADELPHIA, PENNSYLVANIA.

CAR-SEAT.

1,051,040.

Specification of Letters Patent. Patented Jan. 21, 1913.

Application filed April 2, 1912. Serial No. 687,958.

To all whom it may concern:

Be it known that I, ARTHUR WHEATLEY, a citizen of the United States, residing at Philadelphia, in the county of Philadelphia 5 and State of Pennsylvania, have invented certain new and useful Improvements in Car-Seats, of which the following is a specification.

My invention relates to improvements in 10 car seats, the object of the invention being to provide a reversible structure which enables the seat to be reversed and one part operate as the back and the other as the seat and vice versa.

15 A further object is to provide improved mounting for the seat members, so that they may be readily shifted from one position to the other, and which enables the parts to be readily assembled and adjusted in accordance with the angle desired for the seat 20 and the back.

With these and other objects in view, the invention consists in certain novel features of construction and combinations and arrangements of parts as will be more fully 25 hereinafter described in the claim.

In the accompanying drawings, Figure 1, is a view in end elevation illustrating my 30 improvements. Fig. 2, is a view in front elevation. Fig. 3, is a fragmentary view on an enlarged scale on the line 3—3 of Fig. 2. Fig. 4, is a fragmentary end view showing the parts in an intermediate position, and Fig. 5, is a view in section through one of 35 the supporting rods.

1, 1, represent supports which are provided with openings 2 for the reception of tube sections 3. Rods 4 project through the tube sections, and through the circular ends 40 5 of metal straps 6. The central tube section 7 is located on a rod 4 between the straps and the ends of rod 4 are screw threaded for the reception of nuts 8, whereby the tube sections and the straps may be clamped 45 together.

9 and 10 represent the two sections of my improved seat. These sections are constructed precisely alike, and are adapted to be upholstered in the ordinary way. It is 50 to be understood that there are two straps 6 on each rod 4. Two of these straps are pivotally connected by brackets 11 with the section 9, and the other two straps are pivotally connected to section 10 by brackets 55 12. The sections 9 and 10 are connected at their ends by links 13 pivotally connected

by pins 14 to the sections and having recessed ends to engage recessed ends of metal bars 15, secured to the ends of the sections and limit the pivotal movement of the sections in one direction. Braces 16 are also provided at the ends of the seat and connect the sections 9 and 10 sustaining the great strain against the back of the seat. 60 Arm frames 17 are also secured on rods 4 and are provided with inwardly projecting pins 18 which support the seat at an incline and hold the back against rearward movement. 65

When it is desired to reverse the seat, the 70 sections 9 and 10 are swung to the position shown in Fig. 4. By swinging them to right or left, the seat may face either way. To reverse the seat, it is therefore necessary to elevate both sections and due to the links 75 13, the seat section may be forced under the back section as far as permitted by the straps 6, and the location of their pivotal connection with the sections. Hence, in accordance with the location of parts, the 80 seat may have any desired depth, while the back will be normal in height. In other words, as it is one of the great questions in car building to provide car seats with high backs and narrow depth of seat, my structure readily lends itself to economical structures with this end in view. The links 85 13 are so constructed as to limit their swinging movement in one direction, so that the 90 position shown in Fig. 1 is an extreme position.

Various slight changes might be made in the general form and arrangement of parts described without departing from my invention, and hence I do not limit myself to the 95 precise details set forth, but consider myself at liberty to make such changes and alterations as fairly fall within the spirit and scope of the appended claim.

Having thus described my invention what 100 I claim as new and desire to secure by Letters Patent is:

A reversible car seat comprising supports, 105 horizontal rods connecting the supports, two seat sections, straps having rotary mounting on the rods and pivotally connected to the seat sections, metal bars secured to the ends of said seat sections and having recessed ends, links pivotally connecting the ends of the seat sections and having recessed ends to engage the recessed ends of 110 the bars, pins on the supports limiting the

downward movement of the seat sections, braces pivotally connecting the seat sections at the ends thereof, and said straps, links, and braces so mounted that the upwardly projecting seat section is maintained over the horizontal seat section in either position of the seats adjustment, substantially as described.

In testimony whereof I have signed my name to this specification in the presence of 13 two subscribing witnesses.

ARTHUR WHEATLEY.

Witnesses:

R. H. KRENKEL,
CHARLES E. POTTS.
